FIG. 1 is a perspective view of the suitcase insert showing my new design;

FIG. 2 is a left side view thereof;

FIG. 3 is a right side view thereof;

FIG. 4 is a front view thereof;

FIG. 5 is a back view thereof;

FIG. 6 is a top view thereof;

FIG. 7 is a bottom view thereof;

FIG. 8 is a perspective view of the suitcase insert in use within a suitcase; and,

FIG. 9 is the cross sectional view taken in the direction of lines 9-9 of FIG. 6.

The appearance of separation, break lines and brackets form no part of the claimed design. The broken lines are for illustrative purposes and form no part of the claimed design.
